UNITED STATES PATENT OFFICE.

ROBERT ESNAULT-PELTERIE, OF BOULOGNE-SUR-SEINE, FRANCE.

PROGRESSIVE CHANGE-SPEED DEVICE.

Application filed June 4, 1925, Serial No. 34,855, and in France June 10, 1924.

My invention relates to a change-speed device of a progressive nature wherein the rollers, which are formed by surfaces of revolution and are symmetrical with reference to their equatorial plane, are adapted to roll, without escaping in sliding, upon two pairs of disks which are revoluble upon the main centre line of the apparatus, the two disks of a given pair being angularly connected together, and one of the pairs being angularly connected with the main driving shaft whilst the other pair is angularly connected with the actuated shaft, the speed being changed by the longitudinal variation of the distance between the disks of a given pair, thereby changing the ratio of the speeds of the driving and the actuated shafts.

Figs. 1 to 6 are diagrams showing the distribution of the efforts in my said device.

Figs. 7 to 12 show a simple constructional form of change-speed device.

Fig. 7 is a lengthwise section.

Fig. 8 is a section on the line X^1-X^2 of

Fig. 7 for the left hand part and on the line X^3-X^4 for the right hand part.

Fig. 9 is a section on the line $Z-Z$ of Fig. 8 showing the disposition of the roller.

Fig. 10 is a 360° development of the helical ramps which are shown in end view in Fig. 11, said ramps being mounted on the disks C^3 C^4 and coacting with the rollers carried by the actuated shaft.

Fig. 11 is a section on the line $U-U$ of Fig. 7, showing an end view of the said ramps.

Fig. 12 is a cross section on the line X^5-X^6 of Fig. 7 for the right hand part and on the line X^7-X^8 for the left hand part.

Figs. 13 to 16 show various forms of the reversing gearing for motor car use.

Figs. 18 to 20 show modified forms of the transmission rollers of the change-speed device Fig. 7.

Fig. 21 shows a device analogous to Fig. 7 but adapted for automatic control.

Fig. 22 is a detail view.

Preliminary statement.—The present preliminary statement has for its object to furnish various explanations concerning the description which follows the same.

Let us consider the system shown in Fig. 1 which consists of four rollers A, B¹, B², C which are supposed to roll upon one another

without friction. If the lengths of their respective radii are represented by the letters indicated upon this figure, it will be at once observed that the ratio between the angular speeds of the axis x and the axis x' will be

$$(1) \frac{\omega x}{\omega x'} = \frac{a^1 b^2}{a^2 b^1}$$

The roller C may be replaced by the ring C' (Fig. 2), and herein the formula for the speed ratio remains the same, the only difference being that the axis x rotates in the contrary direction to the axis x' whereas in Fig. 1 it rotates in the same direction; so that the formula (1) is of a very general nature, save as concerns the rotation of the axes.

To construct a change-speed device by the use of this mechanism, it is sufficient that the ratio

$$\frac{\omega x}{\omega x'}$$

shall be variable at will, and the formula shows that to this effect it will suffice that at least one of the radii in the second term of the equation (1) shall be variable.

The system according to my invention utilizes, instead of the variation of only one of these radii, the simultaneous variation of the two radii b^1 and b^2 ; the radii a^1 and a^2 may remain constant or may be variable. To effect this simultaneous variation of b_1 and b_2 , the system may consist of a tapered roller B (Fig. 3) whose axis y^4-y is parallel to the main axis of symmetry X^1-X and which may approach or recede from the latter while remaining parallel thereto; no lengthwise movement need be given to the tapered roller B.

In these conditions, when the roller A is longitudinally displaced, for instance to the right, as shown in the dotted lines, the roller B will approach the axis X^1-X and will thus tend to move out of contact with the ring C'. If the latter were urged to the left by a spring R or by other appropriated means, it would move in this direction while still remaining in contact; should the roller A be moved to the left, all the displacements will be obviously in the inverse direction.

It is thus observed that if the action of the spring R (or appropriated means) is sufficiently powerful, one may obtain a suf-

ficient pressure between the ring or concave member C' and the tapered roller B, and hence between the latter and the roller A, so that the movement will take place without sliding, and the shaft X¹ may actuate the shaft X after the manner of a set of gearing, but with a speed ratio which is variable at will by the displacement of the roller A.

- 10 It is also observed in the figure that in certain positions, and chiefly in the position shown in Fig. 3, the pressing action will set up two forces F¹ F² which form a couple and tend to move the axis y¹—y out of its 15 position parallel to X¹—X. Due to the small value of the coefficient of friction of two metal pieces in contact, and since no sliding is allowed, these forces F¹ F² should be considerable, and examination will at once 20 show that such an apparatus cannot be practically constructed, because the axis y¹—y, which usually turns at a high speed, must be mounted in straight or ball bearings of an excessive size.
- 25 The member C', as will be noted, should be acted upon by the spring R through the medium of a thrust ball bearing R', since the said spring should abut at its other end against a stationary member, and the tapered roller B must necessarily abut against another thrust ball bearing B' capable of 30 withstanding the effort of the spring.

To complete the device, a third thrust ball bearing must be used, which serves as an 35 abutment (not shown) for the mechanism controlling the lengthwise motion of the roller A. The friction of all these abutments would represent a considerable proportion of the work, and chiefly as concerns 40 the abutment for the tapered roller. It is further noted that the said mechanism, whose operation has been indicated in a diagrammatic manner, could not be made the subject of any practical application, and its mechanical efficiency would be very low, even if 45 such an apparatus could be constructed.

In the following considerations, and to 50 avoid complication in the text, only the members resembling B in Fig. 3 will be designated as "rollers", and the members resembling A and C¹ in the same figure will be designated as "main disks".

The speed-reducing devices, i. e. the devices for changing the speed at a constant 55 ratio, and the change-speed devices, i. e. the devices for changing the speed at a variable ratio, whether of the friction, the roller, or the ball type, have been proposed and sometimes experimented since a long time, and 60 were constructed in many forms.

The first-mentioned type has been produced recently with a very good efficiency, thus enabling the use of such devices for practical operations, but with the second 65 type, this is apparently not the case. Hav-

ing made particular investigations concerning the latter devices, I observed that while a good efficiency can be had for a given speed ratio and the adjacent speed ratios, it is extremely difficult to obtain the proper efficiency for all the speed ratios which are necessary in the operation of a change-speed box, for instance for motor vehicle use.

To meet this latter necessity, the apparatus must simultaneously fulfill certain conditions which have hitherto been fulfilled only in a separate manner, or incompletely, or not at all, in the various known apparatus, and due to the conditions which may be lacking in each particular case, a given apparatus will fail to work in practice, for instance as set forth by way of example in the particular device above described.

The conditions which my apparatus fulfills in a simultaneous manner are as follows:

1. The pressure is applied in such manner that it is exercised only between members having a like angular motion, in order to obviate all abutments subjected to the effect of pressure and the resulting loss of power.

Such main disks as have the same angular motion, will be designated as "pair of main disks".

2. The aggregate of the forces acting upon a pair of main disks is composed according to a zero force and a couple, which could not be obtained by devices comprising a single roller or a single ball.

In the constructional form hereinafter described, this couple, for one of the pairs, is the power couple, and for the other pair, the receiving couple, with the direction inverted.

3. The forces acting upon a given roller at its various points of contact with the concave disks are composed according to a force which is perpendicular to the axis of roller, passing through this axis, and a couple of zero value.

This condition is more clearly set forth by the following decomposition.

(a) Pressure forces, i. e. components which are perpendicular to the tangent plane common to the two members in contact at each point of contact.

For a given roller, and in all the operating positions the aggregate of these forces constitutes system in equilibrium, i. e., it is composed according to a zero force and a zero couple.

(b) Entrainment forces, i. e. components situated at each point of contact in the tangent plane above specified.

For a given roller, and in all the operating positions, the aggregate of these forces is composed according to a force perpendicular to the axis of this roller and passing through this axis and a zero couple.

4. The tangent planes above specified are in all the operating positions as nearly par-

allel as possible to the main axis of rotation, in order to reduce to a minimum the component of pivotatation at each point of contact. The exact parallel position cannot be attained, since this would prevent the variation of the speed ratio, as observed in Fig. 3, admitting that the cone is converted into a cylinder.

5. I employ more than three rollers, and 10 preferably more than four, but the pressure is collective and without the use of means for distribution of the forces, so that if one of the rolling surfaces has softer portions which would wear more rapidly, such points 15 will be relieved because they are somewhat concave, and at this time the other rollers will take up the load.

This condition is quite important as concerns the wear, and it cannot be fulfilled by 20 the systems for the automatic equalizing of the efforts on each roller nor by the systems without equalizing which comprise three rollers, in which the play between the parts necessarily serves to equalize the action; it is fulfilled very imperfectly by the 25 analogous systems comprising four rollers.

6. The automatic pressure is not proportional to the couple producing the same, but its proportion to the latter varies from one 30 operative position of the apparatus to the other, depending upon the outline of the roller.

Obtainment of these desiderata in my said apparatus.—Figs. 4, 5 and 6 are diagrammatic views of the main disks and one of the rollers, in the simplest form of the apparatus, which contains 5 rollers equally spaced around the main axis X^1-X of the apparatus. The main disks $C^1 C^2$ are connected 40 together as to their angular motion, but may be longitudinally separated or brought together in such manner that they are displaced constantly through equal distances and in the inverse direction.

45 It is observed in Figs. 4, 5 and 6 that in virtue of the separation of the members C^1 and C^2 in the aforesaid conditions, and of the constant direction of the axis $K^1 K$, the said axis will approach the main axis X^1-X to a degree depending upon the spacing of the main disks C^1 and C^2 , and inversely, but inasmuch as the motion of the two main disks $C^1 C^2$ is always equal and in the contrary direction, the roller B will not 55 be moved lengthwise.

For this reason, should the disks C^3 and C^4 be urged together by a pressure force, they will be separated or brought together by a movement which is the reverse of the 60 movement given to the disks C^1 and C^2 , and will be given at each instant, like the latter disks, displacements which are equal and in the contrary direction.

65 In view of the considerations, and admitting that the system is so arranged that the

disks $C^3 C^4$ are constantly urged together in a sufficient manner to prevent all slipping, or sidewise sliding, at the points of contact, it will be observed (for instance in Fig. 4) that the ratio between the angular speed of the 70 outer disks and that of the inner disks will be

$$\frac{\omega_{3.4}}{\omega_{1.2}} = \frac{a^2 b^2}{a^2 b^1}$$

In the intermediate position, Fig. 3, $b_1 = b_2$, whence

$$\frac{\omega_{3.4}}{\omega_{1.2}} = \frac{a^1}{a_2}$$

Figs. 4, 5 and 6 show that the values of the different radii are so combined as to produce in Fig. 4:

$$\frac{\omega_{3.4}}{\omega_{1.2}} = 1$$

in Fig. 5:

$$\frac{\omega_{3.4}}{\omega_{1.2}} = \frac{1}{2}$$

in Fig. 6:

$$\frac{\omega_{3.4}}{\omega_{1.2}} = \frac{1}{4}$$

and this will afford variations in the speed 95 ratios between the driving and the actuated shafts which are sufficient for motor car purposes, and such ratios may further be augmented.

In the following description, care must be 100 taken that the disks C^3 and C^4 effect an automatic pressure while determining the longitudinal position of the rollers B, and that the positive control used for the spacing of the disks C^1 and C^2 will effect this spacing while leaving the disks free to assume the longitudinal position which is imparted to them by the rollers B.

The aforesaid arrangement may be said to 110 represent Fig. 3 in double disposition, and persons skilled in the art will at once observe that the symmetrical form herein adopted will obviously comply with the condition 3 above mentioned.

By the use of a pair of driving disks C_1 115 C_2 and a pair of actuated disks $C_3 C_4$, conditions 1 and 2 can further be realized. Conditions 4 and 5 are also complied with. The mechanical element complying with condition 6 is not shown in the three figures. 120

Description of the first form of construction.—Figs. 7 to 12 show a simple form of construction of the apparatus.

Fig. 7 is a lengthwise section. Fig. 8 is a section on the line X^1-X^2 of Fig. 7 for the left hand part and on the line X^3-X^4 for the right hand part. Fig. 9 is a section on the line $Z-Z$ of Fig. 8, showing the arrangement of the roller. Fig. 10 is a development on 360° of the helical ramps 130

which are shown in end view in Fig. 11, these being integral with the disks C^3 C^4 and in cooperation with rollers mounted on the actuated shaft. Fig. 11 is a section on the line U—U of Fig. 7, showing an end view of the said ramps. Fig. 12 is a cross-section of Fig. 7, on the line X^5 X^6 for the right hand part and on the line X^7 X^8 for the left hand part.

10 The main shaft a is driven by the engine and traverses the entire apparatus; it serves for the centering of all the rotating parts, and is centered in turn at its inner ends a^1 in a ball bearing g which will be further referred to. The said shaft has for its object to rotate the pair of tempered and rectified steel disks C^1 C^2 . The disk C^1 is driven directly, through the medium of the balls d serving the purpose of a key and disposed half in the groove e in the main shaft a and half in the groove f in the element c^1 carried by the disk C^1 ; the said element actuates, by like means comprising the balls d^2 (of which no further description need be given), the element c^2 which is carried by the disk C^2 .

In this manner the disks C^1 C^2 are rotated by the main shaft, as stated, but they are free to move lengthwise on the shaft in virtue of the longitudinal play between the balls d and d^2 and the ends of their recesses. To determine the longitudinal spacing between the said disks, the two elements c^1 , c^2 are screw threaded in contrary directions 35 and respectively engage like screwthreaded portions formed in the element i . The use of this disposition will be further set forth under the heading of "Operation".

Upon the disks C^1 C^2 are revolvably 40 mounted a plurality of double tapered members forming the rollers B; each roller is revolvable on its axis k in the ball bearings l which afford a certain lengthwise play relatively to the axis k whose utility 45 will be explained under the heading of "Operation". The rollers B are held at the exterior between the two main disks C^3 and C^4 , and roll upon the same; said disks are mounted upon the respective elements 50 c^3 , c^4 which are held together in rotation by the roller m whose axis is secured to the element c^4 and which is slidable lengthwise in the slot n in the cylindrical part of the element c^3 ; this latter is provided with 55 a helical ramp o having an irregular pitch, and the tubular part of the element c^4 carries a like ramp p . The actuated shaft r has mounted thereon an enlarged portion r^1 carrying the rollers q^1 q^2 q^3 q^4 coacting with 60 the said ramps, whereby the actuated shaft r will be driven by means of the said ramps and rollers.

65 Due to the inclination of the said ramps, there will be obviously produced a lengthwise pressure of the elements c^3 c^4 against

the rollers B, depending upon the load couple on the shaft r ; but the proportion between the couple and the pressure will vary according to the different positions of the parts of the apparatus, i. e. according 70 to the different speed ratios obtained, as will be further set forth.

Fig. 8 is a cross section on the line X^1 X^2 of Fig. 7 for the portion on one side of the centre and on the line X^3 X^4 for the remaining portion; Fig. 9 is a section on the line Z Z of the roller B (Fig. 8) showing the mounting of the axle k of the roller in the fork bracket s which is pivoted to a strong axle t disposed in an enlarged part 80 u^1 of the partition u traversing the main casing v of the apparatus; said bracket allows the roller which it carries to approach or recede from the main shaft a , according to the spacing between the disks C^1 85 and C^2 , while remaining constantly parallel to the axis X^1 X^2 .

Automatic pressing action.—Fig. 10 is a 360° development of the ramps o and p , and shows that the pitch of the ramps increases from the point 1 to the point 2 and is then constant as far as the point 3; when the ramps move according to the arrows, Fig. 10, relatively to the rollers q^1 q^2 q^3 q^4 , it will be noted that they come nearer to 90 each other, and when the rollers attain the point 1, the mutual pressing action of the two ramps, i. e. the pressing action on the disks C^3 C^4 will now be complete, and as above set forth this signifies that the device 100 is in the position of Fig. 4, the ratio being now 1/1.

But when the disks move in the contrary direction, to the arrows Fig. 10, they also become separated, and the disks C^3 C^4 will 105 have a like action. When in the position 3, the device will occupy the position shown in Fig. 6, and the ratio will now be 1/4.

I have found by calculation that for all speeds between the positions 1 and 2, the 110 pressing action is preferably proportional to the driving couple, i. e. it gradually diminishes relatively to the load couple, whence the use of the variable pitch between position 1 and position 2. But calculation also 115 shows that between the positions 2 and 3 the pressing action should be proportional to the load couple, and this portion of the developed ramp is a straight line, i. e. it constitutes a helix of constant pitch. These 120 conditions would be changed if the rollers had an outline different from the double cone with straight generatrices, for instance as shown in Figs. 18, 19 or 20.

Fig. 11 is an end view showing one of the 125 said ramps, and the two corresponding rollers; each ramp consists of two parts which are in the symmetrical position with reference to the main centre line of the apparatus, and it acts upon one of the rollers, 130.

the latter having the diametrical position in order that the resulting pressing effort shall pass through the main centre line.

Operation.—The operation of the said apparatus is as follows:

- The spring R (Fig. 7) urges the two discs C³ and C⁴ together; the engine is gradually coupled to the main shaft *a*, and the latter will actuate the disks C¹ C² which in turn 10 actuate the rollers B and with them the disks C³ C⁴. As soon as the latter are subjected to a resistance from the shaft *r*, the ramps *o p* will exercise a pressing action, and the device will commence operation. 15 The longitudinal position of the element *r*¹ carrying the four rollers *q* is accurately determined by the abutment *w*, and since the ramps *o p* are symmetrical, the two elements *c*³ *c*⁴ are given positive lengthwise 20 movements of a symmetrical nature, in such manner that the rollers B will not be subjected to the displacement of said elements, but will be radially displaced without longitudinal motion. 25 This motion of the rollers exclusively in the radial direction can only correspond to longitudinal displacements, equal and contrary, of the inner disks C¹ C², and since the latter are connected with the member *i* 30 through the medium of screwthreads, equal and contrary, and are unable to rotate on the main shaft, the member *I* will not be subjected to lengthwise displacements whatever may be the position of the disks C¹ C². 35 So, in this device, the angular position of the member *i* relatively to the main shaft is the factor determining the spacing between the disks C¹ C²; this spacing will in turn determine the radial position of the 40 tapered members B; this latter position determines the spacing between the disks C³ and C⁴, thereby determining the position of the set of rollers *q* upon the respective ramps *o p*, and this latter position will 45 finally determine the ratio of the receiving or load couple to the pressing action, whilst the longitudinal position of the set of rollers *q* will act by successive contacts and in the inverse direction in order to determine the longitudinal position of all the 50 parts, and finally the position of the element *i*.

Control of the change-speed device.—In order to change the speed ratio, the element *i* must be rotated upon the main shaft, and for this purpose the said element is provided with a toothed ring *n*² (Figs. 7 and 12) coacting with two planetary pinions *y*¹ *y*² which engage the internal teeth of a ring *z* which is rotatable by means of a tangent screw mounted on the shaft *g*¹. Each of the shafts *y*³ and *y*⁴ of the respective planetary pinions *y*¹ and *y*² carries a second respective planetary pinion *y*⁵ *y*⁶ in engagement with 55 the internal teeth of a stationary ring *z*¹, and

at the interior with the pinion *e*₁ keyed to the main shaft *a*.

When the ring *z* is stationary, the motion of the planetary pinions will effect the rotation of the ring *n*₂ at the same speed as 70 the pinion *e*₁, i. e. the said ring and pinion will have a fixed relative angular position irrespectively of the rotation of the main shaft, but when the ring *z* is rotated, this will give the ring *n*₂ a speed different from 75 *e*₁; in short upon rotating the ring *z* by a certain number of teeth relatively to *z*¹, this will rotate *n*₂ by the same number of teeth relatively to *e*₁, so that the socket *i* may be turned to a known degree relatively to the 80 main shaft, and this will control the distance between the disks *c*¹ and *c*² and hence the ratio of the speeds.

Back motion.—As above stated, the apparatus allows of rotating the actuated shaft 85 at speeds which can be varied in a continuous manner between 1 and 1/4 the speed of the driving shaft, and in the contrary direction to the latter. For motor car use, the said change-speed device may therefore 90 be employed for the forward motion, by disposing the differential pinions in the inverse direction relatively to what is employed in the known devices.

For the back motion, I may mount upon the differential (Fig. 13)—provided with the tapered toothed ring *c*⁵ known per se—a second toothed ring *c*⁶, and by means of an eccentric *e*³ actuated by the lever *l*³ the small controlling pinion *c*⁷ may be laterally moved 95 whereby it will engage with either ring as desired, and this will provide for the rotation of the vehicle axle in either direction, but this arrangement would require a control extending as far as the rear axle. 100

Two other arrangements may be adapted, as follows:

1. *Semi-direct engagement.*—During the forward motion, the actuated shaft of the change-speed device engages the shaft of the universal joint device (Cardan shaft) 110 and drives the latter by a mechanism which is interposed but which forms a unit during this forward motion. For this purpose I may employ the device shown by way of example in Fig. 14 in partial lengthwise section and in Fig. 15 in cross section, it being placed between the shaft *r* extending from the change-speed box and the shaft *r*² proceeding to the Cardan device, wherein 120 a pinion *p*² keyed to the end of the actuated shaft *r* engages the two planetary pinions *p*³ *p*⁴ loosely mounted on the disk *q* which is provided with a female clutch cone. 125

The said disk is revoluble on the socket *d*⁴ and may be secured to the toothed disk *C*⁵ so as to actuate—through the medium of the friction cone *m*²—the shaft *r*² carrying the said cone. The cone *m*² is keyed 130

so as to rotate with the disk C^5 , but is laterally slidable by means of the two rollers m^2 which are controlled by the fork g^2 in such manner as to enter into fixed contact with the disk q . The aggregate $r^2 p^2 p^3 p^4 q^2 m^2 C^5 r^2$ will thus form a unit turning in the same direction as r and corresponding to the forward motion, in virtue of the reversal obtained by the differential. I thus provide for the semi-direct engagement under all speed ratios.

For the back drive, I release the friction member m^2 and secure the disk q to the stationary casing e^4 by means of the brake f^2 which is controlled by the lever l^4 ; herein the shafts of the planetary pinions become stationary, and the pinions, acting as ordinary wheels, will draw with them the disk C^5 and the shaft r^2 in the contrary direction to r and at a speed which is reduced in the ratio of p^2 to C^5 .

The two operations of the fast holding of q by the cone m^2 or by the brake f^2 may be readily obtained by the use of a single lever which acts through the medium of a pivoted bar upon the rod and link gear actuating the brake f^2 , and the fork g^2 .

This arrangement for simultaneous control, which may consist of known means and will necessarily vary according to the case, has not been represented in order to avoid complication in the drawings.

2. *Direct drive*.—It may be necessary to provide for a direct drive, i. e. to actuate the Cardan shaft directly by the driving shaft. Such an arrangement is shown in longitudinal section in Fig. 16 and diagrammatically in cross section in Fig. 17. In these figures, the shaft a of Fig. 7 is continued at a^2 .

To the shaft r is keyed the pinion p^5 engaging two pinions $p^6 p^7$ mounted on the stationary casing e^5 and transmitting—in the inverse direction—the rotation of the shaft r to the toothed disk C^6 which is provided with the claws f^4 coacting through the medium of the sleeve g^3 (controlled by the fork h^3) with the like claws f^6 on the sleeve g^3 , thereby imparting the reversed and reduced motion of the shaft r to the shaft r^2 . This case corresponds to the forward motion when it is desired to use the range of speeds shown in Figs. 7 to 12.

To the toothed disk C^6 is keyed a pinion q adapted to actuate—through the medium of two pinions q^1 and q^2 mounted in the casing e^5 —a toothed disk q^3 which is loose in the said casing; the said disk carries the claws f^1 which can be brought into engagement with like claws f^8 on the sliding sleeve g^3 , thus transmitting the motion of the disk C^6 (reversed and reduced) to the shaft r^2 . This case corresponds to the back motion.

Finally, by engaging the claws f^9 of the said sleeve with the like claws f^8 disposed

on the end a^2 of the shaft a , I directly transmit the motion of the driving shaft a to the shaft r^2 . Herein the direct drive serves only for the maximum speed.

Obviously, the rollers B may have any other suitable shape than that of a double cone, and for instance I may utilize a spherical shape (Fig. 18), a double pear shape (Fig. 19) a cylindrical shape (Fig. 20) or the like. But such shapes appear to be less advantageous than that of the double cone, and particularly, the cylindrical shape will not allow a speed ratio of unity; the spherical shape, while it provides for the constant value of a coefficient which has some importance in the designing of the apparatus, will diminish the efficiency for certain speed ratios. And the efficiency is to be considered as of particular importance in this class of apparatus.

Change-speed device with automatic control (Fig. 21).—Fig. 21 again shows the driving shaft a , the collar i the toothed rings n^1 and e^1 , the planetary pinions $y^1 y^2$, the discs z^1 , and the tangent screw g^1 mounted on the shaft g^1 (Fig. 7). The shaft g^1 , instead of being controlled by the driver himself in either direction, in order to vary the speed ratios, is herein under automatic control.

To obtain this result, the driving shaft a carries two bevel gears 5 and 6 engaging the respective bevel gears 7 and 8, and it will be observed in Fig. 22 that, due to their disposition, the latter pinions rotate in contrary directions. The pinion 7 is keyed to a shaft 9 extending through the hollow shaft 10 of the pinion 8; the shaft 9 has secured to its end a female cone 11, and the shaft 10 carries the female cone 12; these two cones are mounted opposite each other, and have between them a double male cone 13, 14 which is coaxial with the shaft 9 but is rotatable thereon as well as movable lengthwise. The tapered member 13—14 is secured to a casing 15 which is centered in a ball bearing 16 and is urged at its left hand end by the spring 17 which abuts against an adjustable tappet 18.

The aggregate consisting of the casing 15 and the tapered member 13—14 will thus be urged to the right by the said spring which will tend to bring it into contact with the interior of the female cone 12. Upon the casing 15 is mounted the toothed sleeve 19 whose teeth 20 engage the teeth of the gear wheel 21 which is keyed to the shaft g^1 ; the latter serves to control the device for changing the speed ratio, as hereinbefore set forth.

The two heavy masses 22 and 23 acting by centrifugal force are pivoted to the respective axles 24 and 25 which are mounted upon rigid lugs extending from the female cone 12, and when the said masses are subjected to centrifugal force, they act through

the medium of their arms 26 and 27—each having a hooked end (Fig. 21)—upon the sleeve 28; the latter is mounted by easy friction upon the exterior of the female cone 12 and is slideable thereon without rotating, by the use of the key 29 and it thus imparts the pressure of the ends of the arms 26 and 27 to the casing 15 through the medium of the ball bearing 30. In short, the tapered member 13—14 is urged to the right by the spring 17 and to the left by the centrifugal effect of the said masses.

In the following considerations, the term "standard speed" signifies the speed for 15 which the effect of the said spring exactly counterbalances the centrifugal effect of the said masses, and herein the tapered member 13—14 will be in the position of equilibrium between the two female cones 11 and 12, and 20 without contact with either; it will therefore be unable to rotate, since the tangent screw f is irreversible.

Let it be supposed that the speed of the driving shaft a becomes slower for any 25 reason; the effect of the said spring will now exceed the centrifugal effect of the said masses, so that the cone 14 will come into contact with the female cone 12 and will be rotated by the latter, and this will effect the 30 rotation of the casing 15 and its toothed sleeve 19, so that the latter will rotate the pinion 21 and the shaft g^1 through the medium of the toothed portion 20.

I have already set forth the manner in 35 which the shaft g^1 acts through the medium of the tangent screw f , the planetary pinions y^1 y^2 , and the toothed ring n^2 , upon the member i , and finally changes the speed ratio (Fig. 7).

40 In order that the said apparatus shall operate in the proper manner, it is simply necessary that the person skilled in the art shall take due care that the direction of rotation of the pinion 8 and the cone 12, as 45 also the direction of the threads of the screw f shall be such that in the last-mentioned example, the control action shall reduce the speed of the actuated shaft relatively to the speed of the driving shaft g .

50 In these conditions, should the load on the engine be reduced, the speed of the engine will rise to the point at which the centrifugal force of the said masses, increasing with the speed, will counterbalance the 55 effect of the said spring, thus bringing the tapered member 13—14 into the middle position; the latter will then no longer be actuated by the female cone 12, and it will cease to rotate, as also the parts which it 60 actuates, together with the shaft g^1 . The speed ratio of the apparatus will therefore remain at this new value, while the engine has now returned to the standard speed.

Should the speed of the engine exceed 65 the standard rate for any reason, the centrif-

ugal force of the said masses will now overcome the action of the said spring, and the cone 13 will coast at the left with the interior of the female cone 11, so that the latter will now actuate the aggregate comprising the cones 13 and 14, the sleeve 15, the sleeve 19, the teeth 20, the gear wheel 21, the shaft g , the worm f and the toothed ring z . As above stated, the cone 11 rotates in the contrary direction with respect to the cone 12, so that the parts will be rotated by the cone 11 in the inverse direction to what takes place when they are rotated by the cone 12, i. e. the speed of the actuated shaft will exceed that of the driving shaft. The 70 engine is thus braked to a greater degree, and will be slowed down; the centrifugal force of the said masses will hence diminish until it is counterbalanced by the action of the said spring, at which time the tapered member 75 13—14 will resume its position of equilibrium and the apparatus will become 80 inoperative.

It will thus be observed that in virtue of its action upon the change of speed, my said 85 mechanism will constantly restore the engine to the "standard speed." To determine this standard speed as the driver may desire, the stop or tappet 18 for the spring 17 should be 90 adjustable at will; it may for instance be 95 controlled by a fork 31 actuated by a handle 32 which may be set in various positions, for example upon the quadrant 33. It will be 100 simply necessary, for the driver to set the handle in the position corresponding to the speed which he may desire, and the engine will be constantly brought back to this speed in an automatic manner. If the handle 32 is pushed to the left, the said fork will move 105 to the right, thus compressing the spring, and in order to overcome the action of the spring, the centrifugal action of the said masses must be increased. Otherwise stated, the standard speed of the engine increased 110 according as the handle is moved to the left, and inversely, the standard speed decreases for the right hand motion of the handle.

It should however be noted that in certain cases, the member i may attain its extreme 115 position in one or the other direction, while at the same time the extreme ratio of the speeds (maximum or minimum) will not suffice to correct the racing or the slowing of the engine. In this event, the cone which is in friction contact will continue to act, even though the member i is at the end of its stroke, and the mechanism would thus become broken.

To obviate this drawback, the member z 125 may be provided with a stud 34 which, somewhat before the said member attains the end of its stroke, will abut in either direction against a projection 35 disposed on a sliding member 36 which actuates the rod 37 and the rocking lever 38 whereof the outer end 130

controls—by the fork 39—the sleeve 40 which moves together with the sleeve 19 and hence together with the cones 13 and 14, in the lengthwise direction. Should the member 5 25 turn through more than one revolution, it will suffice to interpose between the said member and the projection 35 a reduction gearing device carrying the stud 34 (not shown).

10 Obviously, the several elements should be so disposed as to act in the proper direction. For instance, with the shaft *a* rotating according to the arrow (Fig. 21) the pinion 7 will rotate according to the arrow Fig. 22, 15 and the pinion 8 will rotate in the contrary direction as well as the cone 14 and the sleeves 15 and 19 connected therewith; the shaft *g* will then rotate according to the arrow Fig. 21, and the worm *f* will rotate 20 the member *i* in the clockwise direction.

Should the action of the speed ratio changing device prove insufficient to allow the engine to resume its "standard speed", the stud 34 will abut against the left hand face of the 25 projection 35, thus driving it to the right, and (by means of the lever 38) the socket 40 with the sockets 19 and 15 will be moved to the left, as well as the cone 14 which is thus uncoupled and its action stopped without the 30 intervention of the centrifugal device 22—23.

In the event of racing of the engine which it is impossible to prevent, the action will be the same but in the contrary direction.

Obviously, the details of construction hereinbefore set forth by way of example will not limit the scope of my said invention, and for instance the double clutching device may be replaced by a double coupling of variable construction, or like means may be 25 adopted. It is evident that the stud 34, the projection 35, the sliding member 36, the rod 37 and the lower part of the lever 38 are shown in Fig. 21 to the rear of the plane of the section, and the drawing is somewhat of a diagrammatic nature in order to avoid the use of another figure whereby the description would be complicated.

What I claim is:

1. A progressive change-speed device comprising a driving shaft, an actuated shaft, rollers having a symmetrical shape relatively to their equatorial plane, two pairs of disks upon which the said rollers are adapted to roll without escaping in sliding, means for angularly connecting together the disks of a given pair, means connecting angularly one of the two pairs of disks with the driving shaft, an irreversible mechanism for the positive control of the longitudinal spacing between the pair of disks connected with the driving shaft, two helical ramps connecting the disks of the other pair with the actuated shaft and constantly urging the said disks against the rollers with a suitable pressure, 55 a spring interposed between the two disks

which are connected with the actuated shaft and urging them together even when there is no motion nor opposing couples.

2. A progressive change-speed device comprising a driving shaft, an actuated shaft, 70 four rollers at the minimum which have the symmetrical position about the said driving shaft and have a symmetrical shape relatively to their equatorial plane, two pairs of disks upon which the said rollers are adapted to roll without escaping in sliding, means for angularly connecting together the disks of a given pair, means connecting angularly one of the two pairs of disks with the driving shaft, an irreversible mechanism for the positive control of the longitudinal spacing 75 between the pair of disks connected with the driving shaft, two helical ramps connecting the disks of the other pair with the actuated shaft and constantly urging the said disks 80 against the rollers with a suitable pressure, a spring interposed between the two disks which are connected with the actuated shaft and urging them together even when there is 85 no motion nor opposing couples.

3. A progressive change-speed device comprising a driving shaft, an actuated shaft, 90 four rollers at the minimum which have the symmetrical position about the said driving shaft and have a symmetrical shape relatively to their equatorial plane, two pairs of disks upon which the said rollers are adapted to roll without escaping in sliding, an irreversible nut with right and left hand thread which is angularly connected with 95 the driving shaft and is screwed to the disks of one of the two pairs, means for the angular setting of the said nut upon the driving shaft, two helical ramps connecting the disks of the other pair with the actuated 100 shaft and constantly urging the said disks against the rollers with a suitable pressure, a spring interposed between the two disks which are connected with the actuated shaft and urging them together even when there is 105 no motion nor opposing couples.

4. A progressive change-speed device comprising a driving shaft, an actuated shaft, 110 four rollers at the minimum which have the symmetrical position about the axis of the said driving shaft and have a symmetrical shape relatively to their equatorial plane, pivoted brackets supporting the said rollers, two pairs of disks formed by surfaces of revolution, and upon which the said rollers are 115 adapted to roll without escaping in sliding an irreversible nut with right and left hand thread which is angularly connected with the driving shaft and is screwed to the two disks of a given pair, means for the angular setting of the nut upon the driving shaft, 120 two helical ramps connecting the disks of the other pair with the actuated shaft and constantly urging the said disks against the rollers with a suitable pressure, a spring in- 125 130

terposed between the two disks which are connected with the actuated shaft and urging them together even when there is no motion nor opposing couples.

5. A progressive change-speed device comprising a hollow actuated shaft, a driving shaft traversing the whole mechanism, means for the direct coupling of the two shafts, rollers which have a symmetrical shape relatively to their equatorial plane, two pairs of disks upon which the said rollers are adapted to roll without escaping in

sliding means for angularly connecting together the disks of a given pair, means connecting angularly one of the two pairs of disks with the driving shaft, means connecting angularly the other pair of disks with the actuated shaft, and means for varying the longitudinal distance between the disks of a given pair. 20

In testimony whereof I have signed this specification.

ROBERT ESNAULT-PELTERIE.
